WATCHCASE

Fritz Marti, La Chaux de Fonds, Switzerland

Application August 29, 1938, Serial No. 227,422
In Switzerland July 16, 1938

3 Claims. (Cl. 58—38)

This invention relates to water-tight watchcases, and more particularly to watchcases comprising a case body, a back and an elastic packing disposed therebetween, whereby an elastic device presses said parts uniformly against each other.

The object of the invention resides in the provision of a watchcase of the above stated type, wherein a leaf spring secured to the case body resiliently engages against the back of the case.

The drawing illustrates by way of example one embodiment and two modifications of the invention.

Figure 1 is a plan view of the embodiment showing a wrist-watch case.

Figure 2 is a plan view of the bottom side and Fig. 3 a lateral elevation of said case.

Figure 4 is a section along the line 4—4 of Fig. 1, in a bigger scale than before.

Figures 5 and 6 are similar sections as in Fig. 4, showing two modifications.

The wrist-watch case represented in Figures 1 to 4 consists of a case body and a back 24. The case body is composed of an exterior part 25 and an interior part comprising a metal frame 26 and an unbreakable glass 27. The border of the glass is extended to cover the sides of the frame 26 and is ultimately fixed to the latter by warm pressing.

The back 24 has on its outer face a longitudinal and rectangular recess 28 in which the middle portion of a spring leaf 29 is disposed, the ends 30 and 31 of the latter being bent upwardly and presenting claws 32 which penetrate into grooves 33 of the exterior part 25. The back 24 presents on its interior side and along the circumference thereof an edge 34 which presses into a ring 35 of plastic material, for instance plexi-gum, fitted in a groove provided between the inferior border of the frame 26 and the inferior border of the glass 27.

If the spring 29 is in the position shown on the drawing, the edge 34 of the back 24 will be strongly applied against the elastic ring 35 and, at the same time, the interior part including the frame 26 and glass 27 will be pressed against the top border of the exterior part 25 in which manner an excellent tightness of the watchcase is effected.

In the modification of Figure 5, the watchcase consists again of a case body and a back 44. The exterior part 45 of the case body is provided with a bottom 40 fixed thereto by a locking joint, and the interior part comprises again a metal frame 46 and an unbreakable glass 47 fixed to each

other by warm pressing. The spring leaf 49 which seats again in a recess 48 of the back is covered by the bottom 40 of the exterior part of the case, and the claws 52 of the bent up ends of said spring penetrate into grooves 53 of the interior part 46, 47.

In the modification of Figure 6, however, the interior part of the case body, comprising the metal frame 66 and the glass 67, presents a bottom 60 fixed to the frame by a locking joint, and the back 64 is disposed outside said bottom and is pressed by a leaf spring 69 against an elastic packing seated in the exterior part 65 of the case body, said leaf spring being seated in a recess 68 of said back and having its ends bent up and inwardly to form claws 72 which engage in grooves 73 of said exterior part.

I claim:

1. A water-tight watchcase having in combination a case body composed of at least one part and forming at its bottom a circumferential groove, an elastic packing inserted in said circumferential groove, a back bearing against said packing and a spring leaf extending across said back and resiliently engaging thereagainst, the elongated ends of said spring being bent up and inwardly and adapted to engage with the case body, whereby said packing is uniformly pressed by the back and forced into close contact with the case body. 30

2. A water-tight watchcase having in combination a case body composed of an exterior part provided with a top border and with external grooves, and of an interior part comprising a frame and an unbreakable glass fast to said frame and bearing against said top border, said interior part forming at its bottom a circumferential groove between frame and glass, an elastic packing inserted in said circumferential groove, a back bearing against said packing and having a recess on its outer face, and a spring leaf extending across said back within said recess and resiliently engaging thereagainst, the elongated ends of said spring being bent up and inwardly and adapted to engage the external grooves on the exterior part of the case body, whereby said packing is uniformly pressed by the back and forced into close contact with the interior part which, at the same time, is pressed against the top border of the exterior part of the case body. 45

3. A water-tight watchcase having in combination a case body composed of an exterior part having a bottom locked thereto and a top border, and of an interior part comprising a frame and 55

an unbreakable glass fast to said frame and bearing against said top border, said interior part forming at its bottom a circumferential groove between frame and glass and presenting 5 on opposite sides two external grooves, an elastic packing disposed in said circumferential groove, a back bearing against said packing and having a recess on its outer face, and a spring leaf extending across said back within said recess and

resiliently engaging thereagainst, said spring being entirely covered by the exterior part, and its elongated ends being bent up and inwardly and adapted to engage the external grooves of the interior part of the case body, whereby said packing is uniformly pressed by the back and forced into close contact with said interior part. 5

FRITZ MARTI.
